RAILWAY CAR

William B. Stout, Detroit, Mich., assignor to
 Pullman-Standard Car Manufacturing Company, a corporation of Delaware

Application September 2, 1933, Serial No. 688,000

1 Claim. (Cl. 105—2)

The improvements in air craft made in the last few years by using shapes and lines suited to the performance sought has stimulated the interest of automotive engineers in reforming their designs, and salesmen have again made "streamlining" a theme of sales talk with customary misuse to the deception of the ever gullible public that still buys many oddities as streamline cars. But the fact is that the drop-shaped streamlined body is not suitable for automotive vehicles in general, and is hardly applicable at all to rail cars.

The swiftest bird is shaped for movement through the air that supports it and, in effect, becomes an enveloping stream flowing over the bird from front to rear. The fastest fish is built to move through a supporting stream of water running from head to tail. These natural shapes are streamlined to suit air in one instance, and water in the other. They teach much about air and submarine craft, but give little help on a rail car or train.

A land vehicle is supported on the solid ground and runs through air which has varying motion relative to the land in one respect and relative to the train in another respect; and the air near the ground has different pressure characteristics from free air well above the ground.

The crab and turtle are shaped to rest or move on the earth and let the water flow over them in any direction with little resistance. But water is noncompressible and its motion relative to the crab or turtle is slow—measured in feet or inches per minute. Air, on the other hand, is compressible, and often moves rapidly relative to the earth on which the vehicle is propelled in another direction at high speed.

Theoretically the contour of a car should minimize the resistance of air without regard to the relative direction of flow; and if railroads could be built anew without regard to cost, many problems could be avoided, but any new rail car or train must run on existing tracks within existing track clearances and provide suitable additional room for passengers and space for freight.

Car resistance is made up of parts due to weight (gravity) that appear as track resistance, journal friction, etc., and also parts due to the size and shape of the car that determine the rearward components of wind, actual or relative, and low pressure areas induced by the movement of the car with respect to the air.

Slow-motion moving pictures of a track under a passing train of conventional weight, reveal a movement not unlike that of a primitive suspen-

sion bridge when people walk over it. The cause and the remedy for track and roadbed difficulties are easily determined from such pictures. The excessive weight is the destroyer and must be reduced.

The parts of car resistance in the second group are complicated by the fact that the path of the car, although through the air, is in the vicinity of the earth in shapes that vary from a tunnel through a cut to ties and ballast on a fill or a bridge. Each of these shapes has its own peculiar reaction with the passing car and the intervening air, and makes resistance in proportion as the adjacent surface of the car and the earth approach the relation of a turbine run backwards.

The turbine effect is particularly noticeable between the broken, irregular underside of conventional cars and the cross ties and ballast over which it travels.

Wind pressure from the side, either directly, or any position having a transverse component, has a peculiar effect, of which little has been learned, because the great weight of conventional cars has prevented these transverse forces from showing their real overturning tendencies.

But the reduction in weight of conventional structures would reveal a new problem:—keeping the cars from being blown over.

It is peculiar, but none the less true, that a head-wind at approximately 16° from the direction of travel produces the greatest overturning effect. This is because the pressure on the windward side is aided by the suction or low pressure produced on the opposite side. The conventional car shape fosters this condition both by presenting large flat areas on the windward side and by presenting obstructions of almost every kind to the easy flow of the air from the windward side to the leeward side, which would tend to maintain substantially uniform pressures at opposite sides.

The principal object of this invention is to make a car of a given load capacity, lighter without loss of strength and shock resistance, and faster with less power as compared with prior cars, and also able to hold the track in spite of the greater relative wind velocity at angles to the line of travel which arise from the increased speed, all with appropriate cost; and otherwise suited to existing conditions.

More particularly, it is the aim of this invention to provide a rail car which combines the advantages of reduced air resistance with the modifying requirements dictated by clearance lines

and desired passenger and/or freight carrying capacity.

Further and other objects and advantages will become apparent as the disclosure proceeds and the description is read in conjunction with the accompanying drawings, in which

Fig. 1 is a side, elevational view of a preferred form of the invention, a fragment of the body being broken away to expose one of the driving 10 motors;

Fig. 2 illustrates in plan the air currents that result from the car moving against a 16° wind, the arrow indicating the direction of car movement;

Fig. 3 illustrates the passage of air currents above and beneath the car;

Fig. 4 represents a standard Pullman car moving against a 16° wind;

Fig. 5 illustrates the effect of a cross wind on a 20 standard Pullman car, the scale being the same as that in Fig. 3;

Fig. 6 is a diagrammatic, perspective view showing the general organization of the car;

Figs. 7 through 19, inclusive, are diagrammatic, transverse, cross sectional views of the body framework, the several views being taken on section lines (Fig. 20) corresponding to the respective figure numbers, and like cross sections being indicated by like section numbers; the 30 dotted lines in Fig. 11 indicating the modifications corresponding to section 11'-11';

Fig. 20 is a plan view showing the interior of the car;

Fig. 21 is an enlarged, side elevational view of 35 the car nose, the structural framework being shown in dotted lines; and

Fig. 22 is a front end view of the car.

At the outset, it should be understood that the 40 selection of certain preferred and modified forms of the invention for illustration and description is merely for the purpose of disclosure, for the invention may be variously embodied within the scope of the appended claim.

45 General organization (Figs. 1 and 6, particularly)

It has already been mentioned that high speed and light weight are two of the foremost objects of the invention. But in addition, due consideration must be given to safety of operation, and 50 to the cost of manufacture.

The first broad principle that is utilized in achieving the goal of this invention is to place the operating power as close as possible to its point of application so that not only is the center of 55 gravity of the car kept relatively low, but also it becomes unnecessary to supply the heavy supporting structure that would otherwise be required if the driving equipment were placed at a higher level. Accordingly, a direct drive is used 60 with the power plant mounted on one of the car trucks.

The second broad concept is to divide the power plant into at least two units so that they may be mounted at the sides of the truck and consequently 65 permit the car body to rest relatively low on the supporting trucks. This arrangement, besides placing the principal weight close to the track, has the further advantage that passenger space is not sacrificed in the attainment of a low center of gravity.

The mounting of as heavy an object as a driving motor upon the car truck requires in ordinary practice exceptionally strong supporting elements, for the car truck is subjected to rapid 70 impact loads as the car moves along the track.

The provision of this normally required strength to counteract the impact loads is obviated in the present case by providing resilient wheels which are capable of absorbing a large portion of the impact shock. In this way, an exceptionally light 5 truck may be used even though it carries a driving motor outboard on opposite sides of the truck.

Since the car of this invention is characterized by its light-weight and high speed, its resistance to air becomes an exceedingly important factor. 10 Cross winds which have no marked effect on conventional railway cars may very easily overturn a high speed light-weight car unless the car body is properly shaped to resist the overturning force. Curiously enough, a wind at an angle of 16° to the direction of travel produces the greatest overturning effect and at the same time offers substantial resistance to car movement. Therefore, in order to give the car stability upon the track and to minimize the resistance of air to forward travel, the car body of this invention is shaped with these problems in mind, and, furthermore, with a consideration of such limiting factors as the A. R. A. clearance line, the passenger 20 space required, the appearance of the car, etc. 25

The illustrative embodiment of the invention, which is shown in diagrammatic perspective in Fig. 6, clearly shows the application of the several fundamental concepts mentioned above to the 30 general organization of the car.

The car body, it will be observed, comprises a space framework 50 of metal tubing that is welded together to form a rigid unitary body. The framework is covered by a metal skin 51 which is secured to the framework and assists in resisting 35 torsional strain.

The body is supported by a front truck 52 and a rear truck 53, the former having internal combustion engines 54 and 55 mounted outboard on opposite sides of the truck. The front truck includes wheeled axles 56 and 57, diametrical ends 40 of which are driven by the motors 54 and 55. The other diametrical ends of the axles 56 and 57 are equipped with brake operating mechanism, generally indicated at 58.

The rear truck 53 includes wheeled axles 59 and 60, each of which are braked by mechanism corresponding to the mechanism 58 of the front truck.

The axle of both front and rear trucks are 50 equipped with what may be termed "resilient" wheels, and this term is intended to include all forms of wheels which are inherently resilient, either by the interposition of rubber under shear, pneumatic tires, springs, or by any other means.

The car body rests upon swing bolsters 61 and 62 of the front and rear trucks, respectively, and, preferably, the bolsters are equipped with cantilever springs 63 which are shackled to swing hangers 64 pivotally suspended from the truck frames.

The truck frames of each truck are fabricated 60 of metal tubing welded together in such manner as to produce space frameworks of necessary strength, and at the four corners of each frame, a leaf spring 65 projects toward the adjacent axle where it connects to a journal 66. The point of connection between the projecting spring and the journal is, in each case, beneath the axle, so that the truck is underslung with respect to the axles. 65

Driving and braking forces applied to the car axles are transmitted to the truck frames by 70 radius rod 67. Other radius arms 68 which connect the worm gear casing 69 to a fixed point on the car truck,—in this case, the transmission housing 70,—take the thrust of the driving worm. Braking forces are resisted by torque arms 71 75

which connect the brake housing 72 to the truck frame.

The exterior of the car is best illustrated in Fig. 1, the front of the car being to the right. The body, as will be seen, is elongated and has a tapering blunt nose and tail to reduce wind resistance. The outer surface of the car consists of smooth broad curves well blended together to produce a graceful appearance and at the same time directing the air currents around the car with minimum effort. The windows 13 are flush with the outer skin, and are made stationary as it is contemplated that a forced system of ventilation will be used.

15 The bottom of the car is uninterrupted in outline except for the wheels of the truck which project through the metal skin enveloping the body framework.

20 The interior of the car is shown in Fig. 20, and the reference character 14 designates the motorman's seat, 75 and 76 baggage compartments, 77 the main passenger space, 78 and 79 lavatories, and 80 the observation salon.

25 Body shape

It is totally impractical to shape the car body so that it most effectively reduces wind resistance. In the first place, a perfectly streamlined body presents a somewhat grotesque appearance and 30 certainly is not pleasing to the eye. It may be said that a car shaped so as to offer the absolute minimum resistance to air currents would not respond to the art fundamental, a term which is used in art to signify certain relative proportions 35 which have been found to have grace, symmetry and pleasing appearance. It is, therefore, desirable to sacrifice some of the advantages of reduced wind resistance in order to give the car a graceful appearance.

40 The American Railway Association clearance line (Figs. 3 and 5) imposes another limitation upon the shape of the car. The clearance line, as is well known, fixes the outside limits for car body contour, including all equipment that 45 is carried by the car. No part of the car is supposed to project beyond this limiting line, and all American car builders respect the rule.

A third limiting factor which forces a compromise in the shape of the body is the interior 50 space required for passengers and baggage. The car body must be sufficiently wide at its base to give reasonable seating capacity. But at the top it need not be as wide. The sides of the car may, therefore, taper inwardly toward the top, and this 55 enables cross winds to be properly dealt with.

A body shape which satisfies the three principal requirements set forth above is one which is substantially ovate in cross section and is provided with a tapered blunt nose and tail. Wind tunnel tests have demonstrated that such 60 a shape has low wind resistance both as against a front wind and a cross wind. In addition, the car is graceful, affords ample passenger space, and can easily be made within the American 65 Railway Association clearance lines.

By referring now to Figs. 1, 2, 3, and 7-19, inclusive, a more accurate conception of the body shape may be discerned. It will first be observed that all lines of the body are blended together 70 with smooth broad curves and that there are no projections which impede the flow of air over the surface of the car.

The general ovate, cross sectional shape, as shown in Figs. 7-19 has several distinct advantages over conventional cross sections. Air cur-

rents striking the side of the car (Fig. 3) at right angles to the longitudinal axis of the car are carried along the upper and lower curved surfaces with comparatively little resistance and since the side of the car tapers upwardly, there 5 will be but a small area at the side of the car which produces eddy currents. On the lee side of the car, there is a relatively small low pressure area, as indicated in Fig. 3, for in the same manner that the smooth curves and sloping side 10 wall carry the air currents over and beneath the car on the windward side so also do they tend to reduce the low pressure on the lee side.

A comparison of the air currents in Fig. 3 with those in Fig. 5 shows clearly the advantage of 15 the ovate, transverse, cross section as compared with a standard pullman car.

The shape of the car in plan also contributes to the low wind resistance which it offers to forward movement. Since the nose and tail are 20 blunt and tapered, air currents striking the car from the most unfavorable angle, viz. 16° from the direction of travel, will follow generally the contour of the body and will produce a much smaller low pressure area on the lee side than 25 the ordinary pullman car. (Fig. 4).

It has already been stated that the possibility of overturning the car becomes a very important consideration when the car is made of light weight materials and travels at a high rate of 30 speed. The relatively small low pressure area on the leeward side combined with a reduced high pressure on the windward side effectively eliminate the possibility of overturning the car by wind resistance. The overturning effect is 35 further minimized by the fact that the car body rests relatively low upon the supporting trucks so that the force of the wind acting through the center of pressure, indicated by C. P. in Figs. 3 and 5, has a relatively short lever arm as compared with the lever arm in an ordinary car. The blunt tapering nose and tail in their vertical projection have the same effect upon breaking the wind as the sides of the car have in allowing cross winds to slip easily over and beneath 45 the car.

The transverse cross-sections, taken adjacent the ends of the car, are more truly egg-shaped or ovate than the intermediate sections, but for convenience the term ovate will be used to designate the characteristic shape which includes upwardly tapering side walls and smoothly rounded top and bottom walls. As the intermediate sections are fuller and more nearly round than the end sections, the term "ovate rotundate" 50 may be used to more specifically describe their shape.

The term "ovate rotundate" wherever it appears in the appended claim is used in the sense above described. This term also implies that the car has its greatest width in the region of the floor level and a smaller width in the region of the roof level; also that the curve which joins the bottom of the car to the side walls is of substantial radius as distinguished from a mere 60 filleted edge, with the result that winds striking the car at an angle are passed beneath the car with ease and without turbulence, thus effectively reducing drag and equalizing to some extent the pressure differential on opposite sides of the car. 65

It will be understood that a car body may have an "ovate rotundate" cross-sectional form although the lower portions of the side walls (above the lower curve) are substantially vertical. The essential relationship defined by the 70 75

term "ovate rotundate" is that the body is shaped (consistent with the above) so that when a horizontal wind strikes the car at an angle with respect to the longitudinal axis of the car, there will be a substantially greater tendency for the air to pass over the car than beneath it (disregarding the spacing of the car body from the ground), but that in either case, the air is guided in its path across the car by smooth broadly rounded unobstructed surfaces. It is this increased tendency for the air to pass over a car of ovate rotundate form than beneath it and the spacing of the car body from the ground so that substantial quantities of air can pass beneath the body, that lowers the center of pressure as compared with a car of similar dimension that does not have this tendency (as for example Adams 489,912 and Zimmerman 542,746).

Preferably the car trucks are provided with a metal skin 89 in the form of a pan, which carries out the reduced wind resistance effect, but does not interfere with the relative movement between the truck and body. The pan is secured to the bottom of the truck frame by screws, or other suitable means.

I claim as my invention:

A light-weight, high speed railway car for ground rail service having smooth, continuous and substantially unobstructed surfaces comprising a car body mounted on trucks and having a relatively low center of gravity, nose and tail portions constructed with curves shaped to offer relatively small resistance to head winds and reduce drag respectively, the body as a whole being spaced a sufficient distance from the rail 10 that substantial quantities of air may pass transversely beneath the car body, said body having a substantially uniform ovate rotundate cross sectional form from end to end which gives the body a relatively low center of pressure and 15 which permits side and oblique winds to pass above and below the car body with relative ease and minimum turbulence, the car being of sufficient length so that the ovate rotundate cross sectional form of the car causes the air pressure 20 on the windward side to be reduced, that on the leeward side to be increased, and the tendency of the car to overturn in strong oblique side winds to be held to a minimum.

WILLIAM B. STOUT. 25
